MULTIPLE MAP HOLDER

Filed July 29, 1929

UNITED STATES PATENT OFFICE

WILLIAM B. WILSON, OF CHICAGO, ILLINOIS

MULTIPLE MAP HOLDER

Application filed July 29, 1929. Serial No. 382,049.

This invention relates to a multiple map holder and more particularly to a holder in the form of a roller shade or curtain with which a plurality of maps, charts or display sheets or curtains are adapted to be associated with a main curtain or apron in such a way that any selected map or chart may be conveniently displayed by simply pulling down on a labeled pull strap whereby the maps 5 behind the selected map are adapted to move downwardly with the selected map, while the maps in front of the selected map are adapted to unroll behind the roller and hang in a looped position within the apron forming a 10 part of the device.

It is an object of this invention to provide a multiple map holder wherein a roller has a main curtain or apron secured thereto in addition to a plurality of superimposed maps or 20 charts in such a way that the various maps or charts may be selectively displayed while the main curtain or apron is supported to assume a looped position when the curtain is unrolled while the maps in front of a selected map are 25 adapted to have the ends thereof supported in stationary brackets, permitting the maps to assume looped positions within the apron while the maps behind the selected map are adapted to be lowered simultaneously with 30 the selected map.

It is a further object of this invention to provide a multiple type map holder provided with a curtain or main shade and a plurality of maps or charts which are adapted to be 35 selectively displayed by merely pulling downwardly on a ring carrying labeled strap, one of which is attached to each of the maps.

It is furthermore an object of this invention to provide a roller type multiple map holder wherein a plurality of maps are supported on a roller which is adapted to be operated by pulling downwardly on any one of a plurality of labeled straps connected with the maps, said labeled straps adapted to normally hang in front of the roller device in a readily accessible position and are furthermore adapted to be held in said accessible position by means of a retaining or stop member pivotally supported on the bracket on which 50 the multiple map holder is engaged.

Another object of the invention is to provide a multiple type map holder wherein the labeled ring carrying straps connected to the respective maps or charts forming the device are adapted to hang in a readily accessible position and are prevented from swinging out of said position by means of a retaining member supported above the map roller which also serves as a dust guard to prevent dust from collecting between the ends of the 55 various charts when the device is in its normal or rolled up position.

Still another object of this invention is to provide a roller type multiple map holder wherein a guard apron and a plurality of 60 charts are secured on a roller in such a way that a brace rod in the end of the apron is adapted to be supported on a stationary support so that the apron will assume a looped position for receiving looped portions of a 65 selected number of charts, while the remaining charts are adapted to be lowered with a selected chart which, when lowered, assumes a convex position or shape permitting the subject matter of the selected chart to be 70 readily read or viewed without distortion.

It is another object of the invention to provide a roller type of multiple map holder embracing a roller carrying a main curtain or apron, and a plurality of charts in a predetermined relation with each of said charts having a labeled ring carrying strap attached thereto and suspended over the roller when the apron and maps are rolled up so that any one of the charts may be selectively engaged 85 and pulled downwardly, said apron assuming a looped position to receive a plurality of the charts while the remaining charts, namely those behind the selected chart, are adapted to be lowered in unison with said selected 90 chart.

It is an important object of this invention to provide an improved roller type multiple chart display device of simplified and improved construction whereby a plurality of charts of the roller shade type are associated with a roller shade apron in such a way that the apron will act as a protecting device for the charts when the same are rolled up and will furthermore assume a looped position 100

and act as a pocket for receiving certain of the charts when the remaining charts are simultaneously lowered for the purpose of displaying a selected chart made possible by merely engaging and pulling down on the labeled strap of the selected chart, which strap is normally positioned in a readily accessible position suspended in front of the rolled up apron and charts beneath a pivoted retaining member, provided for the purpose of preventing the labeled straps from swinging into inaccessible positions.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of an improved multiple type map holder embodying the principles of this invention with a selected chart lowered half way in front of the looped curtain apron and behind the hanging straps connected with the respective remaining charts which unwind with the curtain apron and are disposed within said curtain apron beneath a pivoted dust guard and retaining member which acts to retain the straps in an accessible position.

Figure 2 is an enlarged end elevation of the multiple map holder with the curtain apron and the charts completely rolled up and disposed beneath the combination dust guard and strap retaining device.

Figure 3 is a similar end view of the multiple map holder showing a selected chart partially lowered and also illustrating the remaining charts in looped position within the guard apron.

As shown on the drawings:

The reference numeral 1 indicates a wall or other suitable support, having removably or rigidly engaged thereon a mounting board or bar 2 having secured thereon in spaced relation roller supporting brackets 3 and 4, which may be of any standard type for removably receiving and supporting a curtain roller 5 in horizontal position. The bracket arms 3 and 4 project upwardly and outwardly in an inclined position from the supporting board 2 to afford upper inclined edges 6. Integrally formed on each of the brackets 3 and 4 is an upwardly directed plate or arm 7, the upper end of which is twisted or formed to be positioned at right angles with respect to the mounting board 2 to form a bracket plate 8 which is provided with a notch 9 in the upper end thereof.

Attached to the standard curtain roller 5 is one end margin of a main curtain or apron 10, the other end margin of which is provided with a hem through which a reinforcing or stiffening rod 11 is engaged. The ends of

the stiffening rod 11 project beyond the sides of the apron 10 a distance sufficient to permit the ends of the rod to be removably engaged in the notches 9 of the bracket plates 8 as illustrated in Figures 2 and 3 of the drawings. The curtain or apron 10 is adapted to be rolled up on the spring roller 5 in the customary manner. In the present instance, however, the outer end of the apron 10 is adapted to be normally supported in an elevated position by placing the reinforcing or stiffening rod 11 with the ends thereof seated in the notches 9 of the bracket plates 8.

Secured in superimposed relation with respect to one another upon the front surface of the curtain or apron 10 are a plurality of maps, charts or the like designated by the reference numeral 12. The upper end margins of the respective maps or charts are seated in superimposed relation and may be secured either to the outer face of the apron 10 or directly to the spring roller 5, as desired.

The other end margins of the charts 12 are bent over and formed to provide hems 13. Rigidly secured in each of the chart hems 13 is a stiffening rod 14, the ends of which project beyond the side margins of the charts so that when the apron and the charts are completely rolled up on the roller 5, the ends of the chart rods 14 will be positioned to the rear of the roller and above the bracket arms 3 and 4 and above the supported end of the curtain apron 10 as illustrated in Figure 2. The chart rods 14 are of sufficient length to permit the ends thereof to project beyond the brackets 3 and 4. Attached to the hem or rod of each of the maps or charts 12 is a pull strap 15 having a ring 16 engaged in the outer end thereof. As illustrated in Figure 1, the pull straps 15 on the various charts are positioned at space intervals across the front of the map holder and are normally adapted to hang downwardly in front of the rolled up maps or charts to position the rings 16 so that they may be readily engaged by the hands of a person or by means of hooks on the ends of pull rods when the map holder is mounted in a high position on a wall or support.

For the purpose of holding the pull straps 15 in an accessible position in front of the rolled up charts and to prevent said straps from swinging upwardly in back of the roller, a strap control or holding device is provided and comprises a U-shaped or channel shaped frame 17, the ends of the side arms of which are bent at right angles and are pivotally engaged in screw eyes or supporting members 18 fastened in the top of the mounting bar 2 as illustrated in Figures 2 and 3. The pivoted frame 17 is provided with a covering to afford a dust guard or cover over the top of the map holder to prevent dirt and the like from entering between the ends of the charts when the same are in rolled up posi-

tion. As illustrated in Figures 2 and 3, the dust guard and frame 17 are normally adapted to be swung forwardly in an inclined position with the front portion of the frame resting upon the rolled up charts and upon the 5 pull straps 15 to hold said straps in an accessible position. The arms of the guard frame 17 when in the position illustrated in Figures 2 and 3, also serve as a means for retaining the apron rod 11 seated in the notches 10 9 of the bracket plates 8.

The operation is as follows:

A multiple map holder or chart of the class described is adapted to have the roller 15 thereof supported in the ends of the brackets 3 and 4 which are in turn mounted in any suitable position upon a supporting bar 2 or on a wall of a room in which the improved multiple map holder is to be used. 20 When the multiple map roller is mounted in position, the guard frame 17 is pivotally swung upwardly in an out-of-the-way position and the hem end of the curtain or apron 10 is elevated between the brackets 3 and 4 to permit the stiffening rod 11 of the 25 apron to have the ends thereof seated in the notches 9 of the bracket plates 8, as illustrated in Figure 2. Normally, the hemmed ends of the various maps or charts are positioned behind the roller and above the supported end of the apron 10, as illustrated in Figure 2 to permit the projecting end of the stiffening rods 14 of the charts to project beyond the ends of the inclined edges 6 of 30 the roller supporting brackets 3 and 4. The pull straps 15 for the various maps or charts pass beneath the pivoted retaining frame 17 and hang in front of the rolled up maps, as illustrated in Figure 1 to permit any desired map or chart to be displayed. The straps 15 may be labeled to identify the various maps or charts to make it convenient to use the multiple map holder. When it is desired to display a particular chart, a person 35 has merely to select the proper pull strap 15 and pull downwardly on the same, thereby causing the roller to revolve to unroll the selected map together with the other maps positioned behind the same. The maps or charts which are positioned in front or over the selected chart unwind from the roller and loop in the curtain or apron 10, while the pull straps for said charts remain in their normal position projecting from beneath the retaining frame 17.

When the multiple map holder is operated, the rods 14 of the maps or charts in front of a selected map or chart are permitted to slide downwardly over the inclined edges 6 of the roller supporting brackets 3 and 4, as illustrated in Figure 3. When the multiple map holder is operated to display a selected map or chart, the curtain or apron 10, having one end thereof supported on the reinforcing rod 11 engaged in the bracket

plates 8 assumes a looped position with the loop increasing in depth depending upon the distance the selected map or chart is pulled down. The looped curtain or apron 10 thus acts to receive the looped maps or charts, which are disposed in front of the selected chart. To roll the charts back around the roller, any one of the pull straps of the lowered maps may be pulled to release the roller, permitting the roller to rotate to wind up the maps or charts into their normal position with the rods 14 of the charts positioned above the brackets 3 and 4 and with the pull straps hanging in front of the rolled up maps and beneath the guard frame 17. Attention is called to the fact that when a selected map is pulled down or displayed, that the roller rotates forwardly, thereby causing the selected chart to assume a slightly convex shape resulting from the rolled up condition of the chart. The convex surface of the chart permits the map reading matter or pictures contained on the chart to be readily read or viewed without distortion, which is a decided advantage 50 over the old type of multiple maps, wherein the selected charts or maps, when displayed, assume a concave position. By having the ends of the various maps or charts provided with the projecting rods, which are disposed normally above the brackets 3 and 4, the device can be easily operated and affords an arrangement wherein the various charts or maps always assume or are returned to the same relative positions, thereby always 55 maintaining the tension in the roller spring and obviating rewinding of the roller spring.

The improved multiple type map holder may be used for geographical maps, charts, tariff sheets and the like, and may be mounted in position high up on a wall or on a lower support, since the improved arrangement of the ring carrying pull straps is such that a hooked pole or rod may be used to engage any of the rings of the maps when the holder 60 is mounted high on a wall to permit any selected map or chart to be conveniently displayed. In case the holder is mounted in a low position, an operator may personally select and engage the pull strap of any desired 65 map to properly display the same.

The improved pivoted frame or shield 17 is provided to prevent the pull straps from swinging upwardly in back of the roller in an out-of-the-way position in case the roller 70 is accidentally released and rolls up too rapidly.

While the main curtain or apron as illustrated and described in connection with the improved multiple map holder is provided 75 to afford a dust shield for the maps or charts, and also provides means for relieving the various map rods from stresses or strains in the operation of the device, it will, of course, be understood that the main curtain or apron 80

may be omitted without, in any way, changing the operation of the multiple display map device. When the main curtain or apron is omitted, the rods engaged in the hems of the various maps or charts are adapted to serve as a means for supporting the charts which may be looped behind the certain selected map on display.

It will, of course, be understood that many changes may be made and numerous details of construction may be varied through a wide range without departing from the principles of this invention, and it is therefore not purposed limiting the patent granted hereon otherwise than necessitated by the scope of the appended claims.

I claim as my invention:

1. A multiple map holder comprising a roller, a curtain attached thereto, a plurality of superimposed sheets mounted in position adjacent the front side of said curtain, means for supporting the outer end of said curtain to the rear of said roller to cause the curtain to assume a looped position when the sheets are unwound from said roller.

2. A multiple sheet holder comprising a roller, brackets for supporting the same, a curtain having one end thereof attached to said roller, means for supporting the other end of said curtain to the rear of said roller, a plurality of superimposed sheets secured in position adjacent the front side of said curtain, rods carried by said sheets with the ends of said rods projecting beyond the side of said sheets for coaction with the roller supporting brackets, and members connected with said sheets and disposed in an accessible position to permit a selective display of the sheets.

4. A multiple map holder comprising a roller, brackets for supporting the same, a curtain having one end thereof attached to the roller, a rod projecting through the opposite end of said curtain, notch plates on said brackets adapted to removably receive the curtain rod, a plurality of sheets mounted in a superimposed relation adjacent the curtain, rods carried by said sheets with the ends of said rods projecting to permit the same to be normally supported above said roller brackets and above the supported outer end of said curtain, and designating members connected with the sheets and suspended in front of the roller to permit a selective display of any one of said sheets by merely pulling downwardly on the designating member of a desired sheet.

5. A multiple sheet holder comprising a roller, brackets for supporting the same, notched plates forming a part of said brackets, a curtain having one end thereof secured to the roller, a member carried by the other end of said curtain and adapted to be removably engaged in said notched plates, a plurality of superimposed sheets mounted

adjacent the curtain to be rolled and unrolled therewith, rods carried by said sheets for coaction with the roller supporting brackets when the roller is operated, members connected with the sheets to facilitate a selective operation thereof, and means movably supported above the members to normally hold the same in an accessible position to permit of a selective operation of the sheet holder.

6. The combination with a roller curtain, of a plurality of sheets adjacent said roller curtain, and supporting members for the roller curtain and sheets adapted to permit a selected sheet to be displayed with the sheets behind the selected sheet adapted to move downwardly with the selected sheet, while the sheets in front of the selected sheet together with the roller curtain are adapted to assume a looped position behind the lowered sheet.

7. The combination with a roller curtain, of a plurality of sheets connected therewith, and means for causing a selected number of said sheets and the roller curtain to assume a looped position behind a selected sheet when the same is lowered to effect a display of the same.

8. The combination with a roller, of brackets for supporting the same, a curtain having one end thereof secured to said roller and the other end supported by said brackets, a plurality of sheets mounted in superimposed position adjacent the curtain, ring carrying members connected with said sheets to permit a selective operation thereof, and members carried by said sheets to permit the sheets in front of a selected sheet to assume a looped position supported by the brackets, while the sheets behind a selected sheet are adapted to be simultaneously lowered with the selected sheet.

9. The combination with a roller, of means for supporting the same, a plurality of sheets connected with said roller in superimposed relation, pull members connected to the respective sheets and normally disposed in an accessible position to permit a selective display of said sheets, and means pivotally supported above the roller in contact with said pull members to hold the same in an accessible position.

10. The combination with a multiple sheet holder, of a plurality of pull members connected therewith to permit a selective operation of the multiple sheet holder, and a dust guard member mounted above the holder to act as a dust shield for the sheet holder and furthermore serve as a means for retaining the pull members in an accessible position.

11. A multiple sheet holder of the class described, comprising a pair of brackets, notched plates integrally formed thereon, a roller removably engaged in said brackets, a curtain having one end thereof attached to the roller and the other end thereof remov-

5 ably supported in said notched plates, a plurality of sheets mounted in superimposed position adjacent said curtain, pull members connected with said sheets to permit a selective display of the sheets, and a movable shield mounted above the roller and sheets in coaction with said pull members to hold the same in position and prevent the same from swinging backwardly over the roller.

10 11. The combination with a multiple sheet holder of the class described, of pull members connected therewith to permit a selective display of the sheets, and a dust guard frictionally contacting the sheets and coacting with the pull members to normally hold the same in an accessible position.

15 12. The combination with a multiple sheet holder, of pull members connected therewith to permit a selective display of the sheets, and a pivoted guard member mounted above the holder and frictionally contacting the sheets for coaction with said pull members to hold the pull members in an accessible position and furthermore to serve as a dust 20 guard for the multiple sheet holder.

25 13. In a multiple sheet holder of the class described, the combination with a roller, of notched brackets for supporting the same, a curtain having one end thereof connected with said roller, a rod connected with the opposite end of said curtain and adapted to be removably supported in said notched brackets, a plurality of superimposed sheets connected with said roller adjacent said curtain, rods connected with said sheets and projecting beyond the sides of said sheets for coaction with said brackets, designating pull straps connected with the sheets, and ring members carried by said pull straps.

30 14. The combination with a roller, of brackets for supporting the same, and a plurality of sheets connected with the roller in superimposed relation and adapted to be selectively displayed to cause the sheets behind a selected sheet to be lowered simultaneously therewith while the sheets in front of a selected sheet are adapted to assume a looped position behind the lowered sheet and supported by said brackets.

35 15. The combination with a roller of a plurality of sheets connected therewith, and means causing a selected one of said sheets to pass over in front of the roller to effect a display thereof, while the sheets in front of the selected sheet are looped beneath the roller and behind the sheet displayed.

40 16. The combination with a multiple sheet holder of the class described, of pull members connected therewith to permit a selective display of the sheets of said holder, and means supported above the sheet holder and resting upon the sheets to hold the pull members in an accessible position.

45 17. The combination with a multiple type roller curtain, of brackets for supporting the

same, means for selectively operating the multiple type roller curtain to permit one or more curtains to be lowered to display one of said curtains, while the remaining curtains are adapted to be lowered behind the lowered curtain with the ends of said curtains supported by the brackets.

In testimony whereof I have hereunto subscribed my name at Chicago, Cook County, Illinois.
